UNITED STATES PATENT OFFICE.

HENRY W. AVERY, OF CLEVELAND, OHIO, ASSIGNOR OF ONE-HALF TO THE AVERY STAMPING COMPANY, OF CLEVELAND, OHIO, A CORPORATION OF OHIO.

METALLIC RAILWAY-TIE.

SPECIFICATION forming part of Letters Patent No. 768,839, dated August 30, 1904.

Application filed January 6, 1904. Serial No. 187,889. (No model.)

To all whom it may concern:

Be it known that I, HENRY W. AVERY, a citizen of the United States, residing at Cleveland, in the county of Cuyahoga and State of Ohio, 5 have invented a certain new and useful Improvement in Metallic Railway-Ties, of which the following is a full, clear, and exact description, reference being had to the accompanying drawings.

10 This invention is an improvement upon the type of steel railway-ties which are shown in the Taylor patent, No. 525,927. Such ties having specifically the construction shown in Figure 1 of that patent and known commercially as 15 "Chester" ties have been put to practical use and with great success when they have been especially suited to the exact conditions of use. They have, however, been criticized by practical railroad engineers because of their individual unadaptability. For example, when 20 they are built especially to fit rails of a definite size, as sixty-five-pound rails, and are used on straight stretches they are entirely satisfactory; but if it is desired to use heavier 25 rails with the same ties it is only possible to do this by changing the tie-bars and using tie-bars whose rail-holding claws are separated a slightly-greater distance. This is of course 30 practically objectionable, because it involves a considerable loss whenever the size of the rails is changed. Then again it is customary to slightly spread the rails on curves, the spread being greater or less, depending upon the radius of curvature. These Chester ties 35 are not adaptable to such slight modifications of gage. Tie-bars especially constructed for such slight modifications may of course be provided; but to use them it requires that the construction engineer shall carry with him 40 bars of various sizes, as regards the distance between the rail-holding claws, for use under all the varying conditions which arise in the laying of tracks. This is of course very objectionable for reasons wholly apart from the 45 increased cost of making these various-sized tie-bars.

The object of this invention is to render steel ties of the type referred to universally adaptable to rails of different sizes and to various slight changes in gage.

The invention consists in the use, with two chairs having rail-holding claws on their upper surfaces and having transverse slots for the passage of the tie-bar, of a tie-bar made of two parts, each part having upon its upper 55 edge a claw for engaging with the outer edge of the rail-foot, and in providing means for adjustably securing such parts of the tie-bar together, so as to slightly increase or decrease its effective length—that is to say, the distance 60 between the rail-holding claws thereon.

This invention also consists in the more specific construction and combinations of parts hereinafter described, and definitely set forth in the claims.

In the drawings, Fig. 1 is an elevation of one of my improved ties in use. Fig. 2 is a plan view thereof, and Fig. 3 is a perspective view of one of the fish-plates used in connecting the two portions of the tie-bar.

Referring to the parts by letters, A A represent the two chairs, which have flat tops *a* and diverging side flanges *a'*, and each chair is also provided with upturning rail-holding claws *a''*. There is also through the top and 75 the upper part of both side flanges of each chair a slot to which the tie-bar B is fitted. A rail C rests upon the flat top surface of each chair with one of the rail-feet under the claws *a''* and the opposite rail-foot under the claw *b* 80 on the top edge of the tie-bar. To this extent the construction shown is not new.

The tie-bar B in the construction shown is of inverted-T shape, having the vertical web *b'* and the two horizontal flanges *b''*, which extend in opposite directions from the lower edge of the web. This particular shape is not, however, essential to the generic invention. This tie-bar is made of two bars *b'*, which meet about midway between the two 90 chairs, and these two bars are connected in any desired relationship with each other by the fish-plates D and bolts E. It is necessary, however, that this connection between the two parts of the tie-bar shall be absolutely 95 rigid. Therefore the engaging faces of the fish-plates and bar-sections are transversely serrated. Specifically the outer faces of the vertical web of the tie-bar and the upper faces 100 of the two flanges thereof are transversely

serrated. The fish-plates have outwardly-extending flanges δ on their lower edges, which rest upon flanges of the tie-bar, and the inner faces of the vertical parts of the fish-plates and the lower faces of the flanges δ are correspondingly serrated and engage with the serrated faces of the tie-bar. The bolt-holes through the fish-plates are in the form of horizontal slots, which permit the adjustment

10 of the two parts of the tie-bar.

By readjusting the relation of the tie-bar sections the space between the claws on the tie-bar and the claws on the chairs may be varied so as to be able to grasp rail-feet of 15 different widths, and the relative position of one or both of the chairs may be also changed. Wherefore it is clear that the described ties are universally adaptable to different-sized rails and to variations in grade within small

20 limits.

Having described my invention, I claim—

1. A metallic tie composed of two chairs, having transverse slots through them, and having rail-holding claws on their upper faces, 25 combined with a tie-bar composed of two sections which are fitted respectively to the slots in the chairs, and have on the parts of the bar sections which project above said chairs, rail-holding claws, and means whereby to rigidly 30 connect the two sections of said tie-bar, so as to vary the distance between the rail-holding claws thereon.

2. A metallic tie composed of two chairs

which are transversely slotted and have holding claws on their top faces, a tie-composed of two relatively adjustable sect which are respectively fitted to the slot said chairs, and have rail-holding claws their upper edge, fish-plates and bolts for connecting said tie-bar sections, the engag surfaces of said fish-plates and tie-bar sect being transversely serrated.

3. A metallic tie consisting of two ch having flat tops and rail-holding claws exting upward from said tops and an invert slot through the top of the chair and thro both side flanges thereof, with an inverte shaped tie-bar made of two sections which respectively fitted to th. slots in the ch and are provided with a rail-holding formed in the upward-projecting web, sections being transversely serrated, at inner ends, on the outer faces of the ver web, and on the upper horizontal faces of flanges, and angle-iron fish-plates which correspondingly serrated on their inner tical faces and lower horizontal faces, fo gagement with the serrations on the tie sections, and bolts passing through the plates and tie-bar sections.

In testimony whereof I hereunto affix signature in the presence of two witness

HENRY W. AVER
